MOTOR DRIVEN BLOWER UNIT

Joseph M. Cantwell, Albany, N. Y.

Application April 25, 1927. Serial No. 186,287

1 Claim. (Cl. 230—120)

The present invention relates to blowers, and particularly to devices of this character adapted for creating a forced draft in furnaces or the like, and for general use where it is desirable to 5 deliver a comparatively large volume of air in a highly diffused state at comparatively low pressure.

Where blowers of the present type are used for supplying air to the plenum chamber of a furnace or the like, it is practically impossible to 10 maintain a uniform rate of combustion over the entire grate area. These blowers merely create a unidirectional movement of a column of air which, when it enters the plenum chamber, apparently does not create or maintain therein a 15 substantially uniform pressure beneath the fire, but rather a pressure which varies considerably over different zones or areas of the grate. This variation in air pressure or supply causes corresponding variations in the rate of fuel combustion 20 and results in the formation of so called "hot spots" in the fuel bed. These spots, as they develop, permit the passage of an increased amount of air, and thus effect an ever increasing variation in the rate of combustion in the different zones of the furnace.

With these disadvantages of the present blowers in mind, the primary object of my invention is to provide a device of this character which 30 will deliver a large volume of air in such a way that, after leaving the draft tube of the blower, it will become rapidly diffused and intermixed with the surrounding air. Another object is to provide a blower which will deliver a large volume of air to the plenum chamber of a furnace or the like, and in such a way that the development 35 of "hot spots" in the fuel bed will be substantially prevented. Another object is to provide a blower which will deliver a greater volume 40 of air with less power input than is possible with blowers of the present type. A further object is to provide, in connection with a blower of this general character, an automatically operated check damper which will prevent the "back-flow" 45 of air through the draft tube when the blower is not in operation.

With these objects in view, my invention includes the novel elements, and the combinations and arrangements of elements described below and illustrated in the accompanying drawing, in which—

Fig. 1 is a vertical sectional view through the blower with the motor in elevation;

Fig. 2 is a sectional view on line 2—2 of Fig. 55 1; and

Fig. 3 is a view of the fan.

Referring to the drawing, 10 indicates a casing which may be constructed in any suitable manner to provide merely a carrier for the fan, 11, or to also provide a support for a motor, 12, and a draft tube for the blower, as shown. In the embodiment illustrated, an electric motor, 12, is bolted or otherwise secured to the intake end of the casing so that its shaft is substantially coaxial with the axis of the tube, and a fan, 11, is pinned or keyed directly to the motor shaft. The blades of the fan, 11, are preferably, though not necessarily, of the type shown and terminate in close proximity to the wall of the casing.

Within the casing and on the discharge side of the fan, or, in other words, within what is ordinarily termed the draft tube, are a plurality of separate elements, 13, which are designed to give a whirling motion to the column of air impelled by the fan. These elements are carried by the casing and preferably may be cast as an integral part thereof. They might, perhaps, be described as fin-like projections which extend inwardly only a comparatively short distance from the inner periphery of the casing, so that the central portion of the draft tube is unobstructed, and are downwardly inclined or pitched in the direction of rotation of the fan to provide guides for changing the otherwise normal axial movement of the air column to a spiral or whirling movement. The provision of the fins or blades makes the entire area of the blades of the propeller and the blower more effective. The surfaces of these elements against which the air impinges may be plane, helicoidal or otherwise so long as they are adapted to impart a whirling motion to the air, and generally of any pitch desired, although too flat a pitch will cause a slight "puff back" through the intake at high fan speeds and is, therefore, not desirable.

It is well known that the fan, in addition to producing a forward or driving movement of the air, also produces a whirling movement. By placing the fins in the draft tube or casing at the points illustrated in the drawing, that is, with their upper ends just below the fan, and extending them only a short distance (measured axially of the tube), they intercept or pick off the air as it leaves the fan and modify the direct forward movement thereof by imparting a decided whirling movement to the air column, thus augmenting the whirling movement established by the fan. This whirling movement, densifies the air in the outer part of the column and rarefies the air in the center so that a marked increase

in the efficiency of the blower is noted. When the whirling column of air passes the discharge opening in the draft tube and is no longer laterally confined, it becomes highly diffused, spreading 5 out in all directions and thus rapidly intermixing with the air into which it is projected.

In order to protect both the fan and the motor from the detrimental effect of dust or other foreign matter from the ash pit, which usually circulates 10 incident to the opening of the door of the ash pit, I have provided an automatically operable damper, 14, arranged within the draft tube or casing, 10, so that access may be had to the ash pit without subjecting the fan or motor to the 15 effect of dust. This damper is pivoted off center, as at 15, and carries a counter weight, 16, so that it will automatically gravitate to its normal closed position when the motor, 12, is stopped and the current of air through the casing ceases. The 20 damper should fit rather loosely at the sides near the ends of the pivotal axis and this axis should be quite close to the center of the damper, as shown. When the blower is in use, the current of air passing through the casing is utilized to 25 maintain the damper, 14, fully opened, but when it is desired to open the door of the ash pit, the motor is first stopped, thereby allowing the

damper to automatically gravitate to a closed position for the purpose stated.

While I have described my invention in its preferred embodiment it is to be understood that the words which I have used are words of description rather than of limitation and that changes within the purview of the appended claim may be made without departing from the true scope and spirit of my invention in its broadest aspects. 80 85

What I claim is—

In a blower, including a rotating fan of the propeller type, a tubular member through which the air is impelled by the fan characterized by having a plurality of stationary projecting elements inclined to the axis of said member and disposed about the inner surface thereof from points just clearing the discharge side of the fan; the central, major portions of said member being free of obstructions; and said elements being inclined in a direction adapted to cut off only the outer portions of the air column as it leaves the fan and continue, for a short distance, the whirling movement of the air created by the fan; whereby the volume of air delivered by the fan 90 95 100 is substantially increased.
